United States Patent Office.

JOSEPH FRANKLIN, OF SPRINGFIELD, OHIO, ASSIGNOR TO HIMSELF AND
JOSEPH WHITELEY, OF SAME PLACE.

Letters Patent No. 96,416, dated November 2, 1869.

IMPROVEMENT IN AXES.

The Schedule referred to in these Letters Patent and making part of the same.

To all whom it may concern:

Be it known that I, JOSEPH FRANKLIN, of Springfield, in the county of Clark, and State of Ohio, have invented a new and improved Axe; and I do hereby declare that the following is a full, clear, and exact description thereof, reference being had to the accompanying drawings, making part of this specification, in which-

Figure 1 is a view of one side of the improved axe.
Figure 2 is an edge view of the axe.

Figure 3 is a section through the axe, taken in the plane indicated by line $z z$ in fig. 1.

Similar letters of reference indicate corresponding parts in the several figures.

The object of this invention is to improve axes which are used for chopping wood, felling trees, and other purposes, by giving to the sides of an axe, concave surfaces, extending from the thickest portion of the bevelled bit back to the eye, and making the axe the same thickness at the middle of its width that it is at its top and bottom edges, thereby avoiding the objections attending axes having convex surfaces, and abruptly curved cutting-edges, as will be hereinafter explained.

To enable others skilled in the art to understand my invention, I will describe its construction and operation.

The angle $e f f'$, is a right angle, or nearly so, and the angle $f' f' e'$ is slightly obtuse, which makes the back e , of the axe, slightly narrower than the cutting-edge a .

The cutting-edge a is slightly curved from e to e' ,

and is produced by the two bevelled sides $a a$, which terminate, at $b b$, in concavities extending back to the points $b' b'$, just in front of the eye.

From the points $b' b'$ to $e' e$, the axe is the thickest, and the sides may be flat or slightly bulging.

The thickness of the axe at its upper edge, at its bottom edge, and at the middle of its width, is equal, so that a straignt-edge presented to the surface of the axe, crosswise of the same, will lie flat at all points, from the cutting-edge a' to the rear end c .

An axe thus constructed, can be readily sharpened, as there is comparatively little metal to be ground off to retain the acute angle $b' a' b$. Such an axe will not be liable to glance off from a log while cutting, as there is no bulge of metal from points b to b' . It will sink deeper under a given blow than any other axe. It will chip more freely than other axes, as such portion of the bevel $a a$ does its own splitting. It will also bear a thinner edge without liability to break. It is especially adapted for facing posts, or hewing timber, or making wedges, or any similar work.

Having described my invention,

I claim, as a new and improved article of manufacture, and desire to secure by Letters Patent—

The within-described axe, which combines, in its construction, the peculiarities set forth, and substantially as shown in the drawings.

JOSEPH FRANKLIN.
